UNITED STATES PATENT OFFICE.

HORACE T. LUSTER, OF BEREAL, OHIO.

SHOT HOLDING AND MEASURING CABINET.

SPECIFICATION forming part of Letters Patent No. 513,803, dated January 30, 1894.

Application filed March 16, 1893. Serial No. 466,196. (No model.)

To all whom it may concern:

Be it known that I, HORACE T. LUSTER, of Berea, in the county of Cuyahoga and State of Ohio, have invented certain new and useful 5 Improvements in Shot Holding and Measuring Cabinets; and I do hereby declare the following to be a full, clear, and exact description of the invention, such as will enable others skilled in the art to which it pertains to make 10 and use the same.

My invention relates to improvements in shot-holding and measuring cabinets; and it consists in certain features of construction, and in combination of parts, hereinafter described and pointed out in the claims.

A preferable construction of cabinet embodying my invention is exhibited in the accompanying drawings, wherein—

Figure 1 is a front side elevation of the cabinet, portions being broken away and in section to more clearly show the construction. Fig. 2 is a right hand side elevation of the cabinet, partly broken away, and partly in section on line 2—2, Fig. 1. Fig. 3 is an enlarged perspective of a portion of the cabinet showing the outer portion of one of the discharging troughs or chutes. Fig. 4 is an enlarged elevation in section on line 4—4, Fig. 1.

Referring to the drawings, A represents the 30 casing of the cabinet. The cabinet, by means of upright partitions B, is divided into any desired number of supply-compartments or holders C, that are preferably located in the upper portion of the cabinet and closed at the 35 top, in common, by a lid or cover, A', that constitutes the top of the casing of the cabinet and is hinged, at the rear side of the cabinet, as shown at A², Fig. 2.

The bottom C' of compartments or holders 40 C declines forwardly, so as to cause the contents of said holders to gravitate toward the discharging-opening, C², provided at the lower end of the bottom of the compartments or holders. Below the discharging-opening of 45 each holder C is provided a measuring compartment D of predetermined capacity,—a pound, or whatever it may be. Cut-offs or valves for each supply and its measuring-compartment are provided and operatively 50 connected in such a manner that the cut-off or valve at the discharge-opening of the supply-compartment is opened simultaneously

with the closing of the cut-off or valve for the measuring-compartment, and vice versa, and normally, by means of a spring or otherwise, 55 the cut-offs or valves are held in position opening the discharge-opening of the supply-compartment and preventing any discharge from the measuring-compartment. A preferable construction is shown in the drawings where- 60 in the measuring-compartments have, respectively, a combined tilting-back and declining-bottom, D' representing the back-proper and D² the bottom-proper; said combined back and bottom being adapted to operate nicely 65 between the side-walls of the compartment; the back-proper, at its upper end, having an inwardly-projecting flange, d', that constitutes a cut-off or valve for closing and opening the discharge-opening of the respective 70 supply-compartment, and the lower end of the bottom-proper constituting a cut-off or valve for opening and closing the discharging-end of the measuring-compartment.

The combined tilting-backs and bottoms of 75 the measuring-compartments of the cabinet are preferably loosely mounted, in common, upon a rod, d, that is suitably supported by and extends transversely of the cabinet through partitions B. The bottom-proper of 80 the combined tilting-backs and bottoms of the measuring-compartments have operatively connected therewith, respectively, a rod or stem, d², that extends forwardly through a suitable hole or perforation, a, in the front 85 side of the cabinet and terminates, at its outer end, in a head, d³. The measuring-compartments are preferably provided, respectively, with a spring, S, attached at one end to the back-proper of the combined tilt- 90 ing-back and bottom, and at its other end to the declining bottom of the supply-compartment and acting in the direction to hold said combined tilting-back and bottom in its normal position, which is that of establishing 95 open communication between the supply and measuring-compartment, as shown in Fig. 2, and closing the discharging-end of the measuring-compartment.

By the construction hereinbefore described, 100 it will be observed that upon pushing or actuating rod or stem d² inwardly, the combined tilting-back and bottom of the measuring-compartment will be actuated or tilted to close

communication between the supply and measuring compartments and to open the discharging-end of the measuring-compartment and thereby discharge the contents of the latter.

E represents troughs located below the discharging-ends of the measuring-compartment and extending forwardly through and being suitably supported by the front side of the cabinet, the latter being slotted, as at a', for the purpose, said troughs being adapted to catch the contents of the respective measuring-compartment and conduct the same to the front side of the cabinet where it is conveniently received. The troughs, preferably just forward of the front side of the cabinet, are provided, respectively, with a cut-off or valve, e, that is preferably pivoted, as at e', to the front side of the cabinet, the object of said cut-off or valve being to arrest or prevent the passage of any shot that may, perchance, by jarring of the cabinet and consequent jarring of the cut-offs or valves of the respective supply and measuring-compartment, or otherwise, escape from the measuring compartment into the trough. Hence, cut-off or valve e is kept normally closed, and in taking shot from the cabinet the operative first opens said cut-off or valve and catches, by means of his hand or otherwise, any shot that may have accidentally found ingress into the trough and puts the same back into the respective supply-compartment before effecting the discharge of the contents of the measuring-compartment.

What I claim is—

1. In a shot-holding and measuring-cabinet, a supply compartment having a declining bottom and a discharge-opening at the lower end of said bottom, a measuring-compartment below said discharge-opening, a cut-off or valve for establishing open relation between said compartments and being normally open, a cut-off or valve for opening and closing the discharging-end of the measuring-compartment and being normally closed, suitable means for simultaneously operating said valves or cut-offs to close communication between said compartments and open the discharging-end of the measuring-compartment, and suitable means acting to retain said valves or cut-offs in their normal position, of a trough below the discharging-end of the measuring-compartment, said trough being provided with a cut-off or valve, substantially as and for the purpose set forth.

2. In a shot-holding and measuring-cabinet, a supply-compartment having a declining bottom and a discharge-opening at the lower end of said bottom, a measuring-compartment below said discharge-opening, a

cut-off or valve for establishing and closing open relation between said compartments and being normally open, a cut-off or valve for opening and closing the discharging-end of the measuring-compartment and being normally closed, suitable means for simultaneously operating said valves or cut-offs to close communication between said compartments and open the discharging-end of the measuring-compartment, and a single spring, S, acting to retain said valves or cut-offs in their normal position, of a trough, E, below the discharging-end of the measuring-compartment and provided with a cut-off or valve, e, substantially as and for the purpose set forth.

3. In a shot-holding and measuring-cabinet, a supply-compartment, provided with a discharge-opening, and a measuring-compartment, below said opening, said measuring-compartment having a combined tilting-back and bottom, the back-proper, at its upper end, having a cut-off or valve for closing and opening the aforesaid discharge-opening, and the lower end of the bottom-proper constituting a valve or cut-off for opening and closing the discharging-end of the measuring-compartment, said valves or cut-offs normally establishing open relation between said compartments and closing the discharging-end of the measuring-compartment, suitable means for actuating said combined back and bottom to close the discharge-opening of the supply-compartment and open the discharging-end of the measuring-compartment, and suitable means for automatically returning said back and bottom to their normal position, substantially as set forth.

4. A shot-holding and measuring-cabinet composed of a casing A, upright partitions, B, dividing the cabinet into supply-compartments, C, provided, respectively, with a declining bottom, C', and with a discharge-opening, C", measuring-compartments, D', valves for closing and opening the discharge-openings of the supply-compartment and normally open, valves for opening and closing the discharging-ends of the measuring-compartments and normally closed, springs, S, and means substantially as indicated for operating said valves, troughs, E, and means for preventing the discharge of said troughs, the parts being arranged substantially as and for the purpose set forth.

In testimony whereof I sign this specification, in the presence of two witnesses, this 11th day of February, 1893.

HORACE T. LUSTER.
